UNITED STATES PATENT OFFICE.

GEORGE F. WAELDE, OF HILLSDALE, NEW JERSEY.

SHEET-METAL-LAYOUT TOOL.

Application filed April 15, 1926. Serial No. 102,355.

This invention relates to tools for laying out the bends or folds to be made in a sheet of metal in the formation of moldings, cornices and various other sheet metal articles, 5 trimmings and the like; and the object of the invention is to provide a tool of the class described which is so constructed as to facilitate the quick layout of predetermined dimensions and markings on a workpiece and 10 especially in the production of a given pattern, shape or form in a multiplicity of workpieces whereby the time required in the marking of workpieces is reduced to a minimum; a still further object being to provide 15 a device of the class specified which is movably mounted in connection with a work bench whereby the same may be moved into operative and inoperative positions; a further object being to provide a tool of the 20 class described, the face of which is provided with a plurality of staggeredly arranged apertures adapted to receive a predetermined number of pointed devices whereby the markings or layouts may be made on a 25 workpiece and accurately arranged within comparatively small dimensions; and with these and other objects in view, the invention consists in a device of the class and for the purpose specified which is simple in 30 construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a plan view of a part of a work 40 bench showing my improved tool mounted thereon.

Fig. 1^a is a view similar to Fig. 1, but showing only a part of the construction and showing a modification.

Fig. 2 is a sectional side view of the construction shown in Fig. 1.

Fig. 3 is a section on the line 3—3 of Fig. 2.

Fig. 4 is a detail view of a workpiece 50 which it is desired to be produced by the use of my improved layout tool.

Fig. 5 is a plan view of a workpiece showing the layout or markings thereon to produce the sample illustrated in Fig. 4; and,

Fig. 6 is a sectional detail view of a modified form of construction which I employ.

In the drawing 10 represents a table or work-bench of any kind or class and at 11 I have indicated a hinge bracket secured to one side edge of the work-bench and to 15 which my improved layout tool 12 is pivotally mounted as seen at 13. The tool 12 is of channel formation in cross section and in use, the channel is directed downwardly and the upper flat face is provided with a 20 plurality of staggeredly arranged apertures 14 which in the construction shown in Figs. 1, 2 and 3 of the drawing are threaded to receive one of a number of pointed pegs 15, the points 16 of which project through the 25 top face of the tool 12.

It will be noted that the apertures 14 are arranged in diagonal rows transversely of the top face of the tool and the apertures of one row are in spaced arrangement and 30 intermediate the apertures of adjacent rows when viewed transversely of the tool as clearly seen in Fig. 1 of the drawing.

The side portions of the tool are provided at the upper face thereof with projecting 35 flanges 17 whereby a gage 18 having hook-shaped ends 19 may be coupled with the tool and moved longitudinally thereof and retained in different positions of adjustment by a set screw 20. The gage 18 serves as a 40 square edge against which a workpiece 21 is placed in the use of the tool, the workpiece 21 being in the form of a sheet of metal which may be of any desired length but preferably of predetermined width.

In Fig. 6 of the drawing, I have shown a slight modification wherein I have substituted for the screw pegs 15, tapered pegs 22 which are adapted to seat in countersunk apertures 23 in the top plate of the tool 12 45 with the points 24 thereof projecting above the upper face of said tool and the inner ends 25 projecting slightly to permit of the removal of the pegs 22 by tapping the same with a hammer or in any other desired manner. The construction shown in Fig. 6 will 50 facilitate the quicker attachment and detach-

ment of the pegs. It will be understood that either form of construction may be employed.

It will be understood that the apertures 14 and 23 extend from one end of the tool to the other, only a few of the apertures being shown to simplify the illustration. In Figs. 1 and 2 of the drawing, I have shown an arrangement of the pegs 15 in the tool to produce the finished product 26 seen in Fig. 4 of the drawing from the workpiece 21 or from a strip of metal of predetermined width and of indefinite length. It will be understood that the gage 18 is first adjusted to the desired position on the tool 12 to bring one of the apertures 14 in the tool, such distance from the edge of the gage that when a peg 15 is inserted in said aperture as seen at x , Fig. 1, the first marking y on the workpiece will be formed, which marking will indicate the first bends 26^a to be formed in the resulting product. Another peg is inserted into another aperture as at x^2 to form the second marking y^2 and the second bend 26^b note Figs. 1, 4 and 5, and other pegs designated at x^3 , x^4 , x^5 , x^6 , x^7 and x^8 are arranged on the workpiece to provide markings y^3 to y^8 inclusive on the workpiece to produce the remainder of the bends formed in the finished product seen in Fig. 4 of the drawing. The dotted lines in Fig. 5 of the drawing indicate the bends or fold lines, but it will be understood that all that is applied to the sheet or workpiece 21 are a series of fine punched holes or impressions, and these markings may be arranged at one place only on the sheet or at spaced intervals if desired.

According to the present procedure, it is customary to lay out a templet or pattern piece and with the use of this pattern piece and a punch or pointed tool, the workman stamps by hand each and every marking designated by the templet or pattern piece, and this operation is repeated over and over again in the production of a multiplicity of similar workpieces. With my improved construction, after a desired arrangement of the pegs has been produced in the tool and the gage 18 fixed in proper position, all that is necessary for the workman to do is to lay a sheet or workpiece upon the tool with one edge thereof abutting the gage 18, and by the use of a hammer or other tool, the workpiece is tapped or struck longitudinally of the tool preferably adjacent the arrangement of pegs thereon to form the markings y to y^8 therein. In this way, the desired result is accomplished in a quick and accurate manner, it being borne in mind that all of the workpieces will be correspondingly and accurately marked.

It will be understood that my invention is not limited for use in workpieces of the class indicated in the drawing, nor is my im-

proved tool necessarily limited to the specific use herein described, and various changes in and modifications of the construction herein set out may be made within the scope of the appended claims without departing from the spirit of my invention or sacrificing its advantages.

In Fig. 1^a of the drawing, I have shown a slight modification of the arrangement of the apertures in the top face of the tool 75 where the apertures 14^a are arranged in angular rows 26 and 27 in such manner that the apertures in one row 27 are intermediate the apertures of adjacent rows 26 when viewed transversely or at right angles to the longitudinal plane of the tool, thus providing a closer spacing of the apertures as will be apparent.

Having fully described my invention, what I claim as new and desire to secure by 85 Letters Patent, is:—

1. A tool of the class described comprising an elongated body provided on one face thereof with a plurality of staggeredly arranged apertures adapted to receive marking elements, marking elements adapted to be arranged in a predetermined number of the apertures of said body to produce a predetermined layout on a workpiece, and a gage device adjustably mounted on said body and adapted to be retained in predetermined position with reference to at least one of the apertures in said body.

2. A tool of the class described comprising an elongated body provided on one face thereof with a plurality of staggeredly arranged apertures adapted to receive marking elements, marking elements adapted to be arranged in a predetermined number of the apertures of said body to produce a predetermined layout on a workpiece, a gage device adjustably mounted on said body and adapted to be retained in predetermined position with reference to at least one of the apertures in said body, said marking elements having pointed ends adapted to project above one face of said body and to engage a workpiece placed thereon, said marking elements being in threaded engagement with said apertures, and means for movably supporting said body in connection with a work-bench.

3. A tool of the class described comprising an elongated body of channel formation in cross section, the top face of said body having a plurality of apertures spaced, longitudinally thereof and in staggered relation and into which a predetermined number of marking devices are adapted to be placed, a gage member adjustable longitudinally of said body, and means for retaining the same in different positions of adjustment.

4. A tool of the class described comprising an elongated body of channel formation

in cross section, the top face of said body having a plurality of apertures spaced longitudinally thereof and in staggered relation and into which a predetermined number of marking devices are adapted to be placed, a gage member adjustable longitudinally of said body, means for retaining the

same in different positions of adjustment, and a bracket for hingedly mounting the tool in connection with a suitable support. 10

In testimony that I claim the foregoing as my invention I have signed my name this 12th day of April 1926.

GEORGE F. WAELDE.
